UNITED STATES PATENT OFFICE.

CHARLES Q. C. LEIGH, OF CHICAGO, ILLINOIS, ASSIGNOR TO LEIGH BANANA CASE COMPANY, OF CHICAGO, ILLINOIS, A CORPORATION OF ILLINOIS.

BANANA-CRATE.

1,247,292.

Specification of Letters Patent. Patented Nov. 20, 1917.

Application filed September 30, 1915. Serial No. 53,230.

To all whom it may concern:

Be it known that I, CHARLES Q. C. LEIGH, a citizen of the United States, and a resident of the city of Chicago, county of Cook, 5 and State of Illinois, have invented certain new and useful Improvements in Banana-Crates, of which the following is a specification.

My invention relates to crates and packages for protecting bananas during shipment from one location to another, and more particularly to a device of this character wherein a bunch of bananas may be inserted within and secured to a flexible envelop and 10 the latter suspended from the staves or hoops of a suitable protecting crate or cage constructed of wood or other rigid or semi-rigid material.

In the manufacture of crates for the 20 transportation of bananas and other fruit, it has been the practice to form the envelop or bag, in which the bananas are inserted, of burlap, canvas, drilling, or other similar coarsely woven fabric, and to secure this 25 bag so made within a partially completed cage by disposing the upper edge or mouth of the bag between the two upper hoops or between one upper hoop and the upper end portions of the staves, after which the 30 staves, hoops and bag are tightly and firmly fastened together by means of transverse nails or brads driven through the same.

With the construction just described, it 35 was practically impossible to repair either the bag or the cage without removing the upper hoops which caused the damaging of said hoops, and the upper portions of the staves, and not infrequently tearing the bag, so that the cost of material and labor necessary to repair a crate would almost equal 40 the cost of a new crate.

My invention has for its principal object the construction of a banana shipping package wherein the bag and the cage are so 45 assembled that they may be readily separated for the purpose of repairing either the one or the other and then reassembled without difficulty. Another object of my invention is the provision of a shipping crate 50 wherein the bag and cage are so constructed that they may be finished separately and then connected together to form a complete crate. Still another object of my invention is the provision of a suitable metal ring in 55 the mouth of the bag whereby the latter is

adapted to be retained in its opened position at all times and to facilitate assembly and which metal ring adds materially to the stability of the completed structure. Other objects of my invention will be obvious to 60 others skilled in the art, after an understanding is had of the drawings, and I prefer to accomplish the divers objects of my invention by the means and in the manner hereinafter set forth.

Reference being had to the accompanying drawings forming a part of this specification, it will be observed,

Figure 1 is a vertical side elevation of my improved banana shipping crate.

Fig. 2 is a top plan of a fragmentary portion thereof, and

Fig. 3 is a transverse vertical section thereof taken on line 3-3, Fig. 2, looking in the direction indicated by the arrows and 75 drawn to an exaggerated scale.

It will be seen the crate preferably comprises a cage portion that is constructed of a plurality of hoops 5, 5, that are spaced apart and connected to one another by a plurality 80 of elongated staves or slats 6, 6, that are secured to the outer circumferences of said hoops substantially parallel to each other and to the axis of the crate. These staves may be either single or double staves, but 85 I prefer to employ the latter to secure additional strength. Suitable supplementary hoops 7, 7, are secured externally to the upper and lower ends of the staves for the purpose of reinforcing, strengthening and retaining the same in shape. The upper inside 90 hoop 5^a is not secured to the extreme end of the staves but its upper edge is spaced a slight distance below the end edges of the staves for the purposes to be hereinafter described.

The bag or sack 8 that is adapted to be inserted inside the cage thus formed for containing the bunch of bananas is preferably constructed of burlap, duck, drilling or other 100 similar woven fabric of a coarse mesh, and the lower edge thereof is brought together and tied to form an inverted conical or a funnel-shaped bottom 9.

The cover member 10 for closing the upper open end of the bag comprises a strip of material similar to that of which the bag body is formed and is sewed or stitched thereto preferably in the following manner:—The cover strip is inserted inside the 110

bag until the upper edges of both the bag and cover register, and these edges are then folded inside upon themselves to form a hollow or tubular plait 11 by stitches 12. A metal ring 13 is inserted in the plait 11 either before the stitches are made or the same may be inserted through a suitable slit after the stitching; in the latter event the ring 13 will necessarily be a split ring in order that the insertion may be properly made. The ring 13 is of a diameter corresponding with the diameter of the hoop 5^a, and serves not only as a means for assisting in securing the bag in position within the cage, but also retains the mouth of the bag in open position at all times and adds to the strength of the crate.

In assembling, the bag is inserted bottom first into the cage until the ring 13 and plait 11 surrounding the same, rest upon the shoulder formed by the upper edge of hoop 5^a and the upper portion of the staves 6. Suitable staples, hooks or other similar elements 15 are then driven through the plait into the staves 6 and outer hoop 7 for the purpose of securing the bag in position at the top of the cage. After being thus assembled, the bag is preferably tied to the hoops 5 by means of cords or ropes 16 and, as the bag is of a smaller diameter than the diameter of the cage throughout its body portion, these suspension cords prevent the bag striking the hoops and staves of said cage. In locating these cords or ropes 16, I prefer to place them on the hoops adjacent the staves for the purpose of protecting the same from wear and the rough usage to which the crate is subjected in handling and shipment.

Whenever it is desired to remove the bag for the purpose of repairing either the bag or the crate, the cords 16 are disengaged

Copies of this patent may be obtained for five cents each, by addressing the "Commissioner of Patents, Washington, D. C."

from the hoops and the staples 15 withdrawn, when the bag and crate may be separated without injury to either.

While I have illustrated and described certain specific means for carrying out my invention, it, of course, will be obvious that various modifications and refinements thereof are possible without materially departing from the spirit of my invention. I therefore desire it understood that all such changes are contemplated within the scope of my invention as expressed in the appended claim, and I do not necessarily limit myself to the precise structure shown and described.

What I claim is:

A crate comprising longitudinal staves and transverse connecting hoops, an interiorly disposed supplemental hoop spaced from the top of the crate, a separate ring, means holding the ring within the crate and immediately above the supplemental hoop, a flexible bag suspended from said ring, the top portion of the bag being passed under and over said ring, a closure for the mouth of said bag comprising a separate strip of flexible material having a folded back portion at its lower end disposed around said ring and within the top portion of the bag around said ring, and a line of stitching passing through the superposed portion of the bag and closure whereby said bag is firmly secured to said ring against accidental displacement.

Signed at Chicago, county of Cook and State of Illinois, this 24th day of September, 1915.

CHARLES Q. C. LEIGH.
